UNITED STATES PATENT OFFICE.

JAMES L. MCQUARRIE, OF MONTCLAIR, NEW JERSEY, ASSIGNOR TO WESTERN ELECTRIC COMPANY, OF NEW YORK, N. Y., A CORPORATION OF ILLINOIS.

TELEPHONE TOLL DEVICE AND CIRCUITS THEREFOR.

1,117,215.

Specification of Letters Patent.

Patented Nov. 17, 1914.

Application filed October 12, 1912. Serial No. 725,491.

To all whom it may concern:

Be it known that I, JAMES L. MCQUARRIE, a citizen of the United States, residing at Montclair, in the county of Essex and State 5 of New Jersey, have invented a certain new and useful Improvement in Telephone Toll Devices and Circuits Therefor, of which the following is a full, clear, concise, and exact description.

10 This invention relates to telephone toll apparatus and systems and more particularly to mechanism and a circuit therefor for charging the number of successful calls originated by a telephone subscriber, although not exclusively limited to such use.

15 One object of this invention is to provide an improved and reliable toll device and toll line system for charging the number of successful calls.

20 Another object is to provide means which may be operated to automatically produce a distinctive warning signal for the operator or the subscriber, or for both.

25 This invention will be fully understood from the following description taken in connection with the accompanying drawings in which,—

30 Figure 1 is a perspective view of the mechanism assembled, with certain parts broken away to more clearly exhibit the method of its operation; Fig. 2 is a perspective view with the working parts separated to clearly show their relation; Fig. 3 is a side elevation with the inclosing case and a 35 part of the base and supporting frame in section; Fig. 4 is a top plan view with the inclosing case removed and the micrometer device in section; Figs. 5, 6, 7, 8 and 9 are detailed views of the construction shown in 40 side elevation; Figs. 10 and 11 are plan detailed views of the micrometer and signal controlling mechanism; and Fig. 12 is a diagrammatic representation of circuit connections showing the invention embodied 45 therein.

50 The base 5 furnishes the support for the registering and signaling mechanism and the inclosing cover 6. A registering train comprising numbered wheels 7, 8, 9 and 10 is supported on a shaft 11, having bearings in a frame member 12. The numbered wheel 10 is secured to the shaft 11 while the other numbered wheels are loosely mounted thereon. A step-by-step motion 55 imparted to the wheel 10 is consecutively

imparted to the wheels 9, 8 and 7 by well known means so that the count may be registered in units, tens, hundreds and thousands. A ratchet wheel 13 rigidly secured to the wheel 10 to impart motion thereto is 60 likewise carried on the shaft 11. At the end opposite the ratchet wheel 13, and preferably outside of the frame member 12, the shaft 11 carries a micrometer device comprising an inner threaded tubular portion 65 14, and an outer threaded tubular portion 15. The inner portion 14 is formed integral with an outer cap or barrel 16, which is provided with slots 17 at intervals about its circumference for a purpose to be hereafter 70 described. Graduations are likewise provided on the circumference in the form of numerals to assist in setting the mechanism for a predetermined number of calls. The inner tubular portion besides having screw 75 threads on its outer surface adapted to mesh with screw threads on the inner surface of the outer tubular portion 15, has an axial hole therethrough threaded to receive a split screw 18 whose function is to correct the 80 zero reading of the micrometer in a way well known in the art. The outer tubular portion 15 is rigidly attached to the shaft 85 11 so as to rotate therewith.

Mechanism for rotating the register train 90 is provided, the initial movement of which is produced by a subscriber when originating a call. Extending upward from the base 5 are posts 25 and 26 each forming a support and bearing for a rotatable shaft 27. The shaft 27 has a lever 28 which projects 95 through a suitable opening in the cover where it may be manipulated by a subscriber to turn the shaft 27 in the direction of the arrow shown in Fig. 2. Loosely mounted on the shaft 27 within the cover is an upwardly projecting lever 29 provided with a pin 30, and a spring 31 secured to said lever and to the frame. A lever 32 rigidly secured to the shaft 27 to be turned thereby engages the pin 30 when rotated, thereby imparting motion to the upwardly projecting lever 29 against the tension of the spring 31. At its upper end the lever 29 carries a stepping pawl 33 pivoted thereto by a pin 34. It will 100 therefore be understood that when the shaft 27 is rotated in the direction of the arrow by lever 28 the pawl 33 is advanced into operative position relative to the ratchet wheel 13. A downwardly projecting lug 35 of the 105 110

frame member 12 carries a stop lever 36 pivoted thereto at 37. A spring 38 secured to the lug 35 and to the lever 36 tends to keep the free end thereof elevated so that the lever takes, approximately, a horizontal position unless otherwise displaced as hereinafter described. The rearwardly projecting end 39 of the pawl 33 is provided with a shoulder 40 which may be engaged by a laterally projecting lug 41 of the lever 36 when the pawl has been advanced by the rotation of lever 28 through the agency of shaft 27 and levers 32 and 29 as hereinbefore described. The pawl 33 is thereupon held in its advanced position until released to rotate the register train as hereinafter described. A shoulder 42 of the pawl 33 is adapted to engage the edge of a hole in the frame member 12 through which the registering wheels project to limit the return movement of the pawl. A holding pawl 43 is positioned to engage the teeth of the ratchet wheel 13 to prevent the same from being rotated by the pawl 33 dragging over the teeth thereof during its forward movement.

In rotating the lever 28 to advance the pawl 33 into operative position relative to the register train, as hereinbefore described, means are also made operable whereby a signal may be communicated to the central office to notify the operator that a connection is desired. A third post 50 projecting upwardly from the base 5 provides a pivoted connection 51 having an upwardly projecting cam-shaped lever 52. A bell crank shaped holding pawl 53 is pivotally supported on the lever 52 at 54 and is provided with a downwardly and laterally projecting lug 55. A spring 56 secured at one end to the lug 55 and at the other end to the frame subjects the lever 52 to lateral and the free end of the holding pawl 53 to downward pressure. A hook 57 on the free end of the holding pawl 53 normally engages a latch 58 on the frame member 12 as shown in Fig. 3. When the lever 28, however, is rotated, a pin 59 on the lever 32 engages the pawl 53, raising the free end thereof about the pivot 54 against the tension of the spring 56 until the hook 57 is disengaged from the latch 58 as shown by the dotted lines in Fig. 9. The unlocking of the pawl 53 allows the spring 56 to rotate the lever 52 about its pivot 51. A pin 60 carried by the upper end of the lever 52 is positioned to engage a contact spring 61 when the lever 52 is displaced by the spring 56, thereby causing the spring 61 to make contact with a second spring 62, as shown by the dotted lines in Fig. 9, completing the signal circuit.

Two uprights 70 and 71 secured to the base 5 support and provide bearings for a shaft 72 on which an inertia wheel 73 is securely mounted. The wheel 73 is preferably

made comparatively heavy so as to be able to exhibit considerable inertia when rapidly displaced. A lever 74 rigidly attached to the shaft 27 is provided with a projecting pin 75 adapted when moved to engage a rib on one of the spokes of the wheel 73, imparting a rotary motion thereto. A spring 76 engaging the lever 74 serves to return said lever and the shaft 27 to normal position when the lever 28 is released. A coil spring 77 secured at one end to a lug 78, fastened to the upright 71, and at the other end to the shaft 72 serves to return the wheel 73 to its normal position when the same has been displaced, by a subscriber turning the lever 28, and released by the operator as hereinafter described. The shaft 27 is likewise provided with a lever 79 rigidly mounted thereon, adapted to engage a bell crank lever 80 pivotally supported on the upright 71 at 85 81. A spring 82 secured to the lever 80 and to the frame subjects said lever to tension tending to cause it to resume its normal position as shown in Fig. 7 when displaced by the lever 29 through the agency of the lever 28. A pin 83 carried by the lever 80 is positioned to engage a notch 84 in the rim of the wheel 73 to lock said wheel in its advanced position. The contact between the pin 83 and the notch 84 likewise holds the lever 80 in an elevated position as shown in Fig. 6. A second bell crank lever 85 pivoted to the lever 80 at 86 serves to unlock the wheel 73 by lowering the lever 80 until the engagement between pin 83 and notch 84 is broken. The unlocking action of lever 85 is under the control of the central office operator as hereinafter described. The post 87 projecting upward from the base and to which one end of the spring 82 is secured serves to hold the free end of the lever 85 elevated.

The wheel 73 is provided with an insulated lug 90 adapted to engage a contact spring 91, which spring when so engaged, contacts with a second spring 92. However, when the spring 91 is not engaged by the lug 90 under the pressure of the coiled spring 77, said spring separates itself from the spring 92 as shown in Figs. 1 and 6. 110 When the wheel 73 is released through the agency of lever 80 the energy stored up in the spring 77 by its displacement, causes said wheel to rotate about its axis; the lug 90 strikes the spring 91 and the tension of the coiled spring 77 and the inertia of the wheel 73 momentarily overcome its resiliency, causing said spring to contact with spring 92. The energy stored up in the springs 91 and 92 during this movement is 115 sufficient to overcome the force of the coiled spring 77 and the inertia of the wheel 73, forcing said wheel to rotate in the opposite direction until the lug 90 disengages with spring 91. The contact between springs 91 120 125 130

and 92 is broken to be again completed when the tension of spring 77 overcomes the inertia of the wheel, forcing the same to again advance the lug upon the springs. This momentary making and breaking of the circuit continues until the wheel 73 is brought to rest with lug 90, holding springs 91 and 92 in contact. It will thus be apparent that if the contact springs 91 and 92 are connected 5 in a circuit to the central office, a flashing signal may be transmitted thereto. The interruptions of the circuit thus produced are, however, ineffective until a predetermined number of calls has been exhausted.

10 Means are provided whereby the advancement of the register train and the release of the above described signal wheel are under the control of the central office operator. An electromagnet comprising the coils 93 is 15 secured to the base 5 and is provided with an armature 94 pivoted at 95. The armature 94 is maintained in a normal or neutral position relative to the poles of the coils 93 by the action of springs and levers in a manner well known in the art, but is adapted to 20 be rotated about its axis in either direction, depending upon the direction of the flow of current through the energizing coils. When rotated in a clockwise direction, as shown in 25 Fig. 7, the armature 94 strikes the end of the bell crank lever 85, if the wheel 73 and the lever 80 have been displaced by the action of lever 28, thereby releasing the wheel 73 by lowering the lever 80 until the pin 83 30 and the notch 84 in the said wheel are disengaged. If the armature is turned in the other direction no such action occurs. Secured to the armature 94 in the plane of its pivotal axis is a lever 96 provided with an 35 upwardly projecting arm 97. Pivoted to the upright arm 97 at 98 and adapted to be moved thereby is a lever 99 with a cam-shaped projection 100 at its free end. The cam-shaped projection 100 is adapted when 40 moved to the right by the armature to disengage the holding pawl 36 from the shoulder 40 of the stepping pawl 33, allowing the latter to actuate the ratchet wheel 13 of the counting train. If, however, the armature 45 is rotated in the opposite direction, the lug 100 does not engage the holding pawl 36 and the train is not advanced.

In order to return the mechanism to its 50 normal position and to open the signal circuit at the contact springs 61 and 62 to insure the setting of the stepping pawl 33, by the manipulation of lever 28 when another call is desired, the armature of the electromagnet separates the springs 61 and 62 and 55 locks the lever 52. The lever 96 carries in its free end a roller 110. The roller 110 when the armature is tilted in either direction engages the cam surface of the lever 52, causing said lever to rotate about the pivot 60 65 51 against the tension of spring 56 until the

hook 57 is beyond the latch 58 as shown in Figs. 8 and 9. The return of the armature to normal position allows the spring 56 to actuate the lever 53 until the hook 57 and the latch 58 are in engagement. An insulated pin 111 projecting from the center of the wheel 110 normally rests in a groove 112 of a cam 113, secured to the spring 61. When the armature is tilted, the pin rides out of the groove upon the cam on either side thereof, depending upon the direction of movement of the armature, and causes the spring 61 to continue its contact with the spring 62 for a short interval. The energizing circuit is therefore not broken until the positive operation of the mechanism is insured. Later in the movement of the armature, however, an insulated pin 115 carried by the lever 99 engages an offset 116 on the spring 62, thus separating springs 61 70 75 80 85 and 62 to open the circuit.

The micrometer device hereinbefore described controls the operation of the warning signal through the agency of mechanism actuated thereby. Pivoted to the frame 90 member 12 at 120 is a lever 121 under the tension of a spring 122. On one side of its pivot 120 the lever 121 is provided with an offset 123 adapted to engage the notches 17 in the barrel 16 of the 95 micrometer device. At the other end the lever 121 is provided with a catch 124. A target 125 is carried on a pivot 126 having a bearing in and projecting through the frame member 12. The pivot 126 carries an arm 127 provided with a notch 128 adapted to be engaged by the catch 124 as shown in Fig. 11 when the offset 123 is in one of the notches 17. This engagement may, however, be broken when the offset 123 100 rides out of a slot 17 upon the outer circumference of the barrel 16. A coiled spring 129 is secured at one end to the arm 127 and at the other end to the frame so that when the said target is locked in the position 105 shown in Fig. 11 it is under tension. When the catch 124 releases the arm 127 the target 125 is rotated together with its axis, by the tension of the spring 129 in the direction 110 shown by the arrow in Fig. 11. A pin 130 115 carried by the target 125 is in a position to strike the lever 131 pivoted to the frame at 132 when the target is thus rotated. An insulated lug 133 carried by the lever 131 is adapted to engage a contact spring 134 120 when the said lever is struck by the pin 130 carried by the target. The contact spring 134 is thereupon forced to contact with a spring 135 which, together with the said spring 134, is adapted to close a branch circuit including the springs 91 and 92, causing the intermittent making and breaking of the circuit thereat to become effected.

At a substation A are located the usual speech receiving and transmitting means, a 130

switch hook and signaling device together with the mechanism peculiar to this invention. The line circuit 136 extending from the substation A to the central office B is connected by conductors 137 and 138 to a resistance 139 which is adapted to compensate for the resistance of the coils 93 when they are removed from the line; and the resistance 139 is connected to contact spring 91 by conductor 140. Conductors 137 and 141 join the line circuit 136 to the coils 93. The contact spring 62 is connected to the opposite terminal of the coils 93 by conductor 142. Contact springs 61 and 135 are connected together by conductor 143 and to ground by conductor 144 while the contact springs 92 and 134 are joined by a conductor 145. It will thus be apparent from an examination of Fig. 12 that the closing 20 of the contact between springs 61 and 62 or the contacts between springs 91 and 92, 134 and 135, will close circuits to the central office, the former including the coils 93 and the latter the resistance 139.

25 In order to limit the movement of the wheel 73 caused by the turning of the lever 28 as hereinbefore described, a stop 146 is positioned to engage the pin 90 carried thereby.

30 The two halves of the target 125 are preferably given a different color as shown by the shaded and unshaded portions in the various figures. When the target is turned to be locked by the catch 124, the unshaded 35 portion is visible to the subscriber through a window 137 in the cover 6. Upon being released, however, the target is rotated by the spring 129 until the shaded portion appears beneath said window, notifying the 40 subscriber that the predetermined number of calls has been exhausted. A window 138 in the cover 6 allows the counting wheels to be seen without removing the cover.

45 At the central office B the line 136 terminates at the tip contact of the usual spring jack 150, with a branch conductor 151 extending to a back contact 152 of a relay 153. An armature 154 of relay 153 is connected by conductor 155 to a relay 156 and thence by conductor 157 to grounded battery 158. The relay 156 controls the signal lamp 159 through its armature 160, conductors 161, 163 and 164 and grounded battery 165. The sleeve contact of the spring jack 150 is connected to ground through conductor 166 and the coil of relay 153. The usual plug 170 has its sleeve contact connected by conductor 171 to a grounded battery 172 while the tip thereof is joined by conductor 173 to two keys 174 and 175. The key 174 has its contact point connected by conductor 176 to a relay 177 and thence by conductor 178 to a grounded source of positive current 179. Key 175 has its contact point connected by conductor 180 to relay 181 and thence by

conductor 182 to a grounded source of negative current 183. Armatures 190 and 191 of relays 177 and 181 respectively are grounded. The relay 177 is provided with a normally open front contact 192 connected by conductors 193 and 194 to a signal lamp 195 and thence by conductor 196 to grounded battery 197. Relay 181 is likewise provided with a normally open front contact 198 which is connected to lamp 195 by conductors 199 and 194. It will thus be readily apparent that when either of keys 174 or 175 are depressed to send current over the line the signal lamp 195 is lighted notifying the operator that the current is flowing.

The apparatus is set for a predetermined number of calls by rotating the barrel 16 until the offset 123 rests in a groove 17, representing the number of calls desired. The target 125 is rotated against the tension of spring 129 until the catch 124 carried by the lever 121 engages the notch 128 in the lever 127. The unshaded portion of the target is thereupon visible through the window 137.

Desiring to make a call, the subscriber turns the lever 28 with its shaft 27 as far as possible in the direction shown by the arrow in Fig. 2 and releases the said lever. This movement of the shaft 27 causes three things to take place within the mechanism; the contact between springs 61 and 62 is closed through the agency of pin 59 carried by lever 32, unlocking the lever 52 and the spring 56 retracting the said lever as hereinbefore described. A circuit is completed from ground at the substation conductor 144, contact springs 61 and 62, conductor 142, coils 93, conductors 141, 137, 136 and 151, back contact 152, armature 154, conductor 155, coil or relay 156, conductor 157 to grounded battery 158. The relay 156 pulls up its armature and the operator is thus notified that a connection is desired by the lighting of lamp 159 over a circuit from grounded battery 165, conductor 164, lamp 159, conductor 163, armature 160 and conductor 161 to ground. The stepping pawl 33 is advanced into operative position relative to the ratchet wheel 13 by the lever 29, to be there held by the offset 41 of the holding pawl 36 engaging the shoulder 40; and the inertia wheel 73 is moved against the pressure of spring 77 by the lever 74 until the pin 90 contacts with the stop 146 in which position it is held by the engagement of pin 83 carried by the lever 80 and the notch 84. The coils 93 are however not energized sufficiently to attract their armature 94 since their resistance is sufficiently high to prevent the passage of operating current therethrough at the voltage of battery 158. The insertion of plug 170 into spring jack 150 energizes relay 153 through 125 conductor 182 to a grounded source of negative current 183. Armatures 190 and 191 of relays 177 and 181 respectively are grounded. The relay 177 is provided with a normally open front contact 192 connected by conductors 193 and 194 to a signal lamp 195 and thence by conductor 196 to grounded battery 197. Relay 181 is likewise provided with a normally open front contact 198 which is connected to lamp 195 by conductors 199 and 194. It will thus be readily apparent that when either of keys 174 or 175 are depressed to send current over the line the signal lamp 195 is lighted notifying the operator that the current is flowing.

a circuit from grounded battery 172, conductor 171, sleeve of plug 170, sleeve contact of spring jack 150, conductor 166, relay 153 to ground. The armature 154 is actuated, 5 separating itself from the back contact 152, breaking the energizing circuit for relay 156, and causing the lamp 159 to be extinguished. If the call is successful the operator depresses one of the keys, for example key 174, 10 completing a circuit from the grounded source of positive current 179, conductor 178, relay 177, conductor 176, key 174, conductor 173, tip of plug 170, tip contact of jack 150, conductors 136, 137 and 141, coils 15 93, conductor 142, contact springs 62 and 61, and conductor 144 to ground. The coils 93 are thus energized in such a direction that the armature 94 is turned in a clockwise direction and the lamp 195 is lighted over a 20 circuit from grounded battery 197, conductor 196, lamp 195, conductors 194 and 193, contact 192, armature 190 to ground. The operator is thus notified that a call is being registered. The pawl 33 is thereupon 25 released by the lever 99 to actuate the counting train one step, and the wheel 73 is released by the lever 85 to intermittently close the contact between springs 91 and 92 as hereinbefore described. The lever 53 is, at the 30 same time, advanced by the roller 110 and locked in normal position by the latch 58 and the circuit is opened at springs 61 and 62 by the pin 115 carried by the lever 99, deenergizing relay 177 and notifying the 35 operator that the registration is completed by the extinguishment of lamp 195. The intermittent opening and closing of contact 91-92 continues after the opening of contact 61-62. The above operation is repeated 40 for each successful call. The outer tubular portion 15 of the micrometer device is turned step by step as the successful calls are registered while the barrel 16 and the inner tubular portion 14 are prevented from 45 so rotating by the action of the offset 123 of the lever 121 being in engagement with one of the notches 17. When the predetermined number of calls is exhausted, the inner end of the screw 18 carried by the 50 inner tubular portion 14 engages the end of the outer tubular portion 15 and the advancement of the train rotates the barrel 16. The offset 123 of lever 121 is thereupon forced to ride out of the notch 17, in which 55 it has been resting, releasing the target 125 so that the shaded portion thereof is visible beneath the window 137, warning the subscriber; and the lever 131 closes the contact between springs 134 and 135. The opening and closing of the contact between 60 springs 91 and 92 is thereupon made effective after the opening of contact 61-62 as hereinbefore described and when the next call is registered by the depression of key 65 174 a flashing signal is provided for the operator by means of the following circuit: ground at the substation, conductors 144 and 143, contact springs 135 and 134, conductor 145, contact springs 92 and 91, conductor 140, resistance 139, conductors 138, 137 and 136, tip contact of jack 150, tip of plug 170, conductor 173, key 174, conductor 176, relay 177, conductor 178, to grounded source of positive current 179. The intermittent flow of current caused by the closing and opening 70 of contact 91-92 causes the relay 177 to attract and release its armature 190, causing the lamp 195 to flash. If, on the other hand, the calls are unsuccessful, the operator sends current through coils 93 in a direction to 75 operate the armature in a counter-clockwise direction by pressing key 175, the circuit being completed from grounded source of negative current 183, conductor 182, relay 181, conductor 180, key 175, conductor 173, 80 tip of plug 170, tip contact of jack 150, conductors 136, 137 and 141, coils 93, conductor 142, contact springs 62 and 61, conductor 144 to ground. When the armature 94 is thus turned, the stepping pawl 33 and 85 the wheel 73 are not released for reasons hereinbefore given, the only effect being that the circuit is opened at springs 61 and 62 and that relay 181 attracts its armature 90 95 100 105 110 115 120 125 130 135 140 145 150 155 160 165 170 175 180 185 190 195 200 205 210 215 220 225 230 235 240 245 250 255 260 265 270 275 280 285 290 5. In combination a manually set electro-
magnetically controlled step-by-step ad-
vanced service meter, a signal transmitter
controlled thereby, and a controlling device
coöperating with said service meter and said
signal transmitter to cause signals to be
given after a predetermined number of
steps.
6. In combination a manually set electro-
magnetically released step-by-step advanced
10 service meter, a signal transmitter placed in
operative position during the setting of said
service meter and allowed to operate upon
the advanced movement thereof, a microm-
eter device advanced step-by-step by said
15 service meter, and means controlled by said
micrometer device after a predetermined
number of steps and coöperating with said
signal transmitter to cause the same to be
20 come effective.
7. In combination a manually set electro-
magnetically released step-by-step advanced
service meter, a signal transmitter placed in
operative position during the setting of said
25 service meter and allowed to operate upon
the advance movement thereof, a microm-
eter device advanced step-by-step by said
service meter, a signal controlled by said
30 micrometer device to be operated after a
predetermined number of calls, and means
actuated by said signal and coöperating
with said signal transmitter to cause the
35 same to become effective.
8. The combination with a telephone toll
device, of a manually set signal transmitter,
40 comprising an inertia device, a spring con-
nected thereto, and circuit contacts con-
trolled thereby; and means for releasing
said inertia device to intermittently open
45 and close said contacts under the influence
of said spring.
9. In combination a manually set electro-
magnetically released step-by-step advanced
service meter, a micrometer device advanced
45 step-by-step by said service meter and a
signal controlled by said micrometer device.
10. In combination a registering mecha-
nism, an actuator therefor, a signal trans-
mitter placed in operative position during
50 the setting of said actuator, a micrometer
device, means controlling said actuator, said
transmitter and said micrometer device, and
means coöperating with said micrometer de-
vice and said signal transmitter to cause the
55 same to become effective.
11. In combination a registering mecha-
nism, an actuator therefor, a signal trans-
mitter placed in operative position during
60 the setting of said actuator, a micrometer
device, electromagnetic means controlling
said actuator, said transmitter and said mi-
crometer device, and means coöperating
with said micrometer device and said signal
65 transmitter to cause the same to become
effective.
12. In combination a registering mecha-
nism, an actuator therefor, a signal trans-
mitter placed in operative position during
70 the setting of said actuator, a micrometer
device, electromagnetic means controlling
said actuator, said transmitter and said mi-
crometer device, and means controlled by
said micrometer and coöperating with said
75 signal transmitter to cause the same to be-
come effective.
13. In combination, a registering mecha-
nism, an actuator therefor, means for setting
said actuator, a signal transmitter placed
in operative position during the setting of
80 said actuator, a micrometer device, means for
releasing said actuator and said transmitter
and operating said micrometer device, and
means coöperating with said micrometer de-
vice and said signal transmitter to cause the
85 same to become effective.
14. In combination a registering mecha-
nism, a manually set actuator therefor, a
signal transmitter placed in operative posi-
tion during the setting of said actuator, a
micrometer device, electromagnetically con-
90 trolled means for releasing said actuator
and said transmitter and operating said mi-
crometer device, and means coöperating
with said micrometer device and said signal
transmitter to cause the same to become ef-
95 fective.
15. In combination a register train, an
actuator therefor, means for setting said
actuator, a signal transmitter placed in op-
erative position during the setting of said
100 actuator, a micrometer device, electromag-
netic means for releasing said actuator to
operate said micrometer device and to allow
said signal transmitter to operate, and
means coöperating with said micrometer de-
105 vice and said signal transmitter to cause the
same to become effective.
16. In combination a register train, a
manually set actuator therefor, a signal
transmitter placed in operative position dur-
110 ing the setting of said actuator, a microm-
eter device, means for releasing said actuator
and said transmitter and operating said mi-
crometer device, and means coöperating
with said micrometer device and said signal
115 transmitter to cause the same to become ef-
fective.
17. In combination a register train
mounted on a shaft, an actuating pawl
therefor, manual means for advancing said
pawl into operative relation relative to said
train, a signal transmitter placed in opera-
tive position by said manual means, a mi-
crometer device mounted on the shaft of
said train to be actuated thereby, electro-
magnetic means for releasing said pawl to
actuate said register train and said mi-
crometer device and to allow said signal trans-
mitter to operate, and means controlled by
said micrometer device for coöperating with
130

said signal transmitter to cause the same to become effective.

18. In combination a register train mounted on a shaft, an actuating pawl therefor to advance the train step-by-step, contact springs, manually actuated means for advancing said pawl and closing the contact formed by said springs, a signal transmitter placed in operative position by said manual means, electromagnetically controlled means for releasing said pawl to actuate said train and for allowing said signal transmitter to operate, a micrometer device associated with

and actuated by the said train in its advancement, and means operated by said micrometer device and coöperating with said signal transmitter to cause the same to become effective. 15

In witness whereof, I hereunto subscribe my name this 11th day of October A. D., 20 1912.

JAMES L. MCQUARRIE.

Witnesses:

WALTER F. HOFFMAN,
ELLA EDLER.
